UNITED STATES PATENT OFFICE

155,007

DESIGN FOR A FLASHHOLDER

Herbert H. Harmon, Rochester, N. Y., assignor to
Eastman Kodak Company, Rochester, N. Y., a
corporation of New Jersey

Application November 23, 1946, Serial No. 135,028

Term of patent 14 years

(Cl. D61—1)

To all whom it may concern:

Be it known that I, Herbert H. Harmon, a citizen of the United States, residing in Rochester, in the county of Monroe and State of New York, have invented a new, original, and ornamental Design for a Flashholder, of which the following is a specification, reference being had to the accompanying drawings, forming part thereof.

In the drawings:

Fig. 1 is a top plan view of a flashholder, showing my new design.

Fig. 2 is a rear elevational view of the flashholder.

Fig. 3 is a perspective view from the rear left-hand corner of the flashholder shown in Fig. 1. The dominant feature of my design resides in that portion shown in full lines.

I claim:

The ornamental design for a flashholder, as shown and described.

HERBERT H. HARMON.
